CLAIM

We claim the ornamental design for a bed hook and adapter, as shown and described.

DESCRIPTION

FIG. 1 is a top, rear, left perspective view of the claimed design, showing environmental structure;

FIG. 2 is a close up view of region 2 of FIG. 1;

FIG. 3 is a rear, left perspective view of FIG. 1, showing environmental structure;

FIG. 4 is a bottom, front, right perspective view of FIG. 1;

FIG. 5 is a rear, left perspective view thereof;

FIG. 6 is a front elevation view thereof;

FIG. 7 is a rear elevation view thereof;

FIG. 8 is a left elevation view thereof;

FIG. 9 is a right elevation view thereof;

FIG. 10 is a top plan view thereof; and,

FIG. 11 is a bottom plan view thereof.

The ornamental design which is claimed is shown in solid lines in the drawings: The broken lines in the drawings are for illustrative purposes only and form no part of the claimed design. Broken lines formed by equal length dashes show unclaimed subject matter.
